Specification for Design.

Patented Oct. 4, 1921.

Application filed March 5, 1921. Serial No. 450,093. Term of patent 14 years.

To all whom it may concern:

Be it known that I, MATTHEW G. VIDULICH, a citizen of the United States, residing at No. 72 Reservoir avenue, city of Jersey City, county of Hudson and State of New Jersey, have invented a new, original, and ornamental Design for a Bottle, of which the following is a specification, reference being had to the accompanying drawing, forming a part thereof, and showing a front view of a bottle embodying my design.

The essence of my invention resides in the general appearance of the bottle, substantially as shown and described. It is to be understood that my claim includes all substantial equivalents of my design as shown and described.

I claim:

The ornamental design for a bottle substantially as shown and described.

MATTHEW G. VIDULICH.
